Primary Examiner — Melanie H Tung*(74) Attorney, Agent, or Firm* — Leydig, Voit & Mayer, Ltd.**(57) CLAIM**

The ornamental design for a computer display with a graphical user interface for a spending analysis tool, as shown and described.

DESCRIPTION

The FIGURE is a front view of a computer display with a graphical user interface for a spending analysis tool.

The broken line drawing of the text, numbers and other graphic elements form no part of the claimed design.

1 Claim, 1 Drawing Sheet
